THREAD MILLING MACHINE

Walter D. Archea, Cincinnati, Ohio, assignor to
 The Cincinnati Milling Machine Company,
 Cincinnati, Ohio, a corporation of Ohio

Application March 8, 1935, Serial No. 10,126

16 Claims.

(Cl. 10—154)

This invention relates to metal working machines and more particularly to an improved machine tool for producing various internal configurations in a work piece.

5 One of the chief objects of this invention is to provide an improved precision thread milling machine which can be efficiently utilized for producing short threads of accurate predetermined length. Such a machine is particularly useful 10 for cutting to exact length the short multiple threads in bottle molds.

Another object of this invention is the provision of a machine of the character described which may be selectively set up for efficiently 15 cutting spiral grooves, such as threads; annular grooves; or a combination of both.

A further object of this invention is to provide 20 an improved multiple thread index angle selector which may be efficiently utilized in threading machines to simplify indexing the work through the correct angle in correspondence with the 25 number of multiple threads being cut.

Another object of this invention is to provide an improved mechanism in threading machines 25 for adjusting the angle of the cutter spindle relative to the work in accordance with the pitch of the thread being cut without necessitating a complicated power drive to the spindle.

Other objects and advantages of the present 30 invention should be readily apparent by reference to the following specification considered in conjunction with the accompanying drawings illustrative of one embodiment thereof, but it will be understood that any modifications may be 35 made in the specific structural details thereof within the scope of the appended claims without departing from or exceeding the spirit of the invention.

Referring to the specification in which like reference numerals indicate like or similar parts:

Figure 1 is an elevation of a machine tool embodying the principles of this invention.

Figure 2 is a section on the line 2—2 of Figure 1 showing the tool supporting and driving means.

45 Figure 3 is a detailed section on the line 3—3 of Figure 2.

Figure 4 is a detailed section as viewed on the line 4—4 of Figure 1 of the means for inter-connecting the tool slide for power movement.

50 Figure 5 is a section through the headstock of the machine taken on the line 5—5 of Figure 1.

Figure 6 is a detail section on the line 6—6 of Figure 1.

55 Figure 7 is a detail section taken on the line

7—7 of Figure 5 showing the transmission means for rotating the work and reciprocating the tool.

Figure 8 is a section on the line 8—8 of Figure 5, showing the details of the control clutch operating mechanism.

Figure 9 is a detail section on the line 9—9 of Figure 8.

Figure 10 is a detail view as shown on the line 10—10 of Figure 7 showing the dial means for indicating the angular extent of a thread.

Figure 11 is a section on the line 11—11 of Figure 7.

Figure 12 is a section on the line 12—12 of Figure 7 showing the details of the yieldable clutch means of the tool head transmission.

Figure 13 is a section on the line 13—13 of Figure 2.

Figure 14 is a detail view of the trip control mechanism showing the parts in starting position.

Figure 14a is an expanded view of the dog carrying drum showing the graduated scale for positioning the control dogs.

Figure 14b is a detail elevational view showing the relative position between the dogs shown in Figure 14a with respect to the trip plungers, the latter being shown in a position for cutting threads of less than a full revolution.

Figure 15 is a detail view of the trip mechanism for axially indexing the trip shaft shown in Figure 14b.

Figures 16 and 17 are detail views showing the clutch trip shaft in other positions when cutting threads involving one revolution or more.

Figures 18, 19, 20 and 21 are views showing the different positions of the multiple thread index angle selector.

Figure 22 is an expanded view in plan of the index selector ring showing the clamping means therefor, and the setting graduations.

Figure 23 is an expanded view of a groove having spiral and annular portions which may be formed in one continuous operation in a work piece in this machine.

One exemplary embodiment of the invention is shown in Figure 1 of the drawings, and although it is obvious that this machine may be utilized for various purposes without departing from the principles of this invention, it is especially useful in forming the internal threads in bottle molds. Due to the wide range in the styles and sizes of bottles having screw caps, the thread in one case may be single as on small bottles; and in other cases—especially in the larger diameters—it may be double, triple, or other multi-

ple threads. It is conventional practice in the bottle making art to start each thread of a multiple thread combination in the radial plane where the next previous thread stopped so that 5 the threads do not as a rule over-lap, with the result that the angular extent of each thread of a multiple thread combination will be equal approximately to 360 degrees divided by the multiple thread index number. It will therefore be 10 seen that the length of the individual threads of a multiple thread combination is of very short angular extent. This machine is designed and adapted to automatically stop the relative feeding movement between tool and work after the 15 work has revolved through the proper angle in accordance with the type of thread being cut and regardless of the number of individual threads of a multiple thread combination.

The machine comprises a bed 10 upon which 20 is mounted a headstock or work support 11; and a tailstock or tool support indicated generally by the reference numeral 12. Separate variable speed prime movers 13 and 14 are provided respectively for rotating the work and rotating the 25 tool, and each prime mover has individual rate control boxes 15 and 16 mounted respectively on opposite ends of the bed. Each control box has a rheostat which is controlled, as by handles 17 and 18 respectively. In other words, each of 30 these handles has a stop position, and is progressively movable from this position to start the motor and gradually increase the speed thereof to the desired rate.

The tool spindle 19 is journaled in a longitudinally movable quill 20, and projects beyond 35 one end of the quill for receiving the driving member 21 which may be in the form of a multiple belt pulley. As shown in Figure 2, the driving member 21 is connected by a motion transmitting band 22 to a source of power such as the pulley 23 secured to the armature shaft 24 of the variable speed motor 14.

The motor 14 is supported or otherwise secured to a plate 24' which is pivotally supported 45 on the pin 25 mounted in a carrier plate 26. The purpose of this pivoted plate is to adjust the tension of the power transmitting band 22, and for this purpose an adjustable screw 27 is threaded into the lower end of the plate and held in 50 suitable position by a lock nut 28. Since the tension is such as to urge the motor and plate in a counter-clockwise direction as viewed in this figure, it is only necessary to provide a suitable boss 29 against which the end of the screw 27 55 may abut.

The quill 20 is supported in a second carrier plate 30 which is mounted on the opposite side of the upright 31 from the carrier plate 26. This upright has a pair of arcuate guides 32 and 33 60 which are generated about the center 34. In other words, the center of the tool 35 which may be either a milling cutter or a grinding wheel must always coincide with the center 34, and the remainder of the parts are swung about this 65 center to vary the angle of the plane of rotation of the tool. The line 36 indicates the radius of the guideway 32 which may be in the form of a rectangular groove as shown in Figure 2 for receiving a similarly shaped projection on the 70 side of the carrier plate 30. A pair of clamping bolts 37 pass through the head 31, the carrier plate 26 and the carrier plate 30, and the axes of these bolts lie on the circumferential line 38 which is the center line of the guide 32.

75 The guideway 33 simply comprises a pair of

arcuate slots formed in the sides of the upright 31 through which a pair of clamping bolts 39 pass, these bolts extending through the carrier plate 30 at one end and the carrier plate 26 at the other end.

The two carrier plates are simultaneously adjustable up or down by means of an elevating screw 40 which, as shown in Figure 2, passes through a pivoted block 41 secured to the upper end of the upright 31 to permit lateral movement of the screw during movement of the carrier plates along their arcuate paths. The lower end of the screw passes through a nut member 42 which is journaled at opposite ends in the carrier plates.

The pairs of clamping bolts 37 and 39 have nuts on one end which are loosened during rotation of the elevating screw by the manually operable handle 43. The angular position of the head is indicated by the arrow 44 which moves over a scale 45 graduated in degrees attached to the rear of the upright 31. It will thus be seen that the cutter spindle may be adjusted a considerable amount above center and a few degrees below center. It will also be noted that the prime mover for the cutter spindle is adjusted with it so that the drive pulleys 23 and 21 always lie in the same plane, thereby eliminating complications in the drive between prime mover and tool spindle.

Since the length of the shank 46 of the cutter or tool may vary depending upon the size of the cutter, and therefore project different distances beyond the end of the chuck 47 in which the cutter is secured, means have been provided for adjusting the quill to compensate for this, and as shown in Figure 13, comprises a worm 48 fixed with the shaft 49 which is journaled at opposite ends in the carrier plate 30 with the teeth inter-engaging spiral rack teeth 50 milled in the side of the quill 20. The end of shaft 49 is hexagon-shaped for receiving a suitable shaped wrench for adjusting the same.

The upright 31 which carries the cutter spindle and the driving means therefor is provided with suitable guide surfaces inter-engaging the guide surfaces of the lateral guideway 51 formed on the upper surface of the longitudinally movable slide 52. The slide 31 is moved by a depending nut 53 threaded on a screw 54 fixed against longitudinal movement in the boss 55. The screw 54 is provided with a hand wheel 56 for effecting rotation thereof, and also a dial 57 for indicating the amount of movement imparted to the slide upon rotation of the hand wheel. In the 55 operation of the machine the upright 31 is moved laterally to the left, as viewed in Figure 2, to disengage the cutter from the work; and is moved toward the right to sink the cutter to the required depth in the work. Since this operation is repeated for each thread, a suitable stop means has been provided to facilitate this movement, comprising a stop bolt 58 threaded in the upright 31, and a lock nut 59 for securing the same in any adjusted position. Upon movement of the upright 31 toward the right, the head of bolt 58 abuts the end of a hardened pin 60 located in the boss 55. When this contact is made, the tool has been sunk to the proper depth in the work.

The support 52 for the cross slide is suitably guided upon the bed 10 and is utilized for moving the cutter toward and from the work, the slide being shown in a retracted or loading position in Figure 1. Since the starting point of 75

engagement between the tool and work must be exactly determined, an adjustable stop has been provided to limit the approach movement of the cutter. This stop means comprises an adjustable screw 61 threaded in a boss 62 projecting from the rear end of member 52 and a lock nut 63 for securing the screw in adjusted position. The end 64 of the screw abuts the end of a rack bar 65 which extends from the fixed headstock 11 through the slide 52.

This rack bar is utilized not only to form part of the stopping means, but also comprises part of the translating means for the slide 52. As shown in Figure 3, the rack bar 65 has teeth 66 cut in one side thereof which are inter-engaged by a pinion 67 which is rotatably mounted in anti-friction bearings 68, as more particularly shown in Figure 2. The pinion has integrally connected therewith a worm wheel 69 which meshes with a worm 70 secured to the end of shaft 71, which shaft projects from the side of the slide 52 and is provided with a manually operable hand wheel 72. If the rack bar is fixed, rotation of the hand wheel will cause translation of slide 52.

From the mechanism thus far described it will be seen that manually operable means have been provided for advancing and retracting the slide 51 to thereby move the tool 34 to and from the work support; and for moving the cross slide 31 to sink the tool in the work.

In the art of cutting threads, it is well known that the cutter or tool must be relatively moved in suitable timed relation with the rotation of the work in order that the thread will have a desired pitch. Power operable means have been provided for this purpose, and the rack bar 65 constitutes the power reciprocator for the slide 52 in addition to its other functions. During power movement of the tool slide, it is necessary that it be securely fastened to the bar 65 and to this end means have been provided as shown in Figure 4, for locking the slide to the rack bar. This means comprises a reciprocable block 73 having a semi-circular face 74 for frictionally engaging the side of the rack bar. This block is connected to the end of rod 75 and a manually operable handle 76 having a cam face 77 is utilized for exerting pressure on the end of bar 75 and frictionally clamping the slide to the rack bar.

The transmission for effecting rotation of the work and translation of the tool slide is shown in Figures 5 and 7. The shaft 78, Figure 5, is operatively connected by means of pulley 79, belt 80, and pulley 81 to the armature shaft 82 of the variable speed motor 13. This shaft has a worm 83 which inter-meshes with a worm wheel 84 secured to the lower end of a vertical shaft 85. A second shaft 86 parallel to the shaft 85 has a change gear 87 secured to the upper end thereof in mesh with a change gear 88 secured to the upper end of shaft 85 whereby the rate of operation of the machine may be further changed. A removable cover plate 89 permits access to these gears for reversing them or substituting gears of other ratios for varying the speed of the transmission.

The shaft 86 has a second gear 90 secured thereto for rotating the gear 91 and thereby the integrally formed bevel gear 92. This bevel gear simultaneously rotates a pair of bevel gears 93 and 94 in opposite directions respectively, which are mounted for free rotation on the shaft 95. This shaft has splined thereon a shifter fork 96

which carries clutch teeth on opposite ends thereof for inter-engagement with similarly formed clutch teeth formed on the opposing faces of bevel gears 93 and 94.

This clutch has an intermediate or neutral position, and power transmitting positions on either side thereof; and is shifted by a fork 97 which is splined on the shaft 98. A spring pressed detent 99 serves to maintain the shifter fork 97 in any one of its three positions.

The shaft 95 has a large worm gear 100 keyed thereto for rotating the worm wheel 101 which, as more particularly shown in Figure 7, is secured as by threaded bolts 102 to the dog carrying wheel 103. This wheel is keyed at 104 to a sleeve 105 which is journaled in the bearing 106. This sleeve has keyed thereto a spur gear 107 for driving gear 108 mounted for free rotation on a shaft 109. Means have been provided for connecting the gear 108 in different ways to the shaft 109, and for determining rotation of a gear 110 keyed to the shaft, this gear driving through spur gear 111 a rotatable member 112 in which may be secured suitable means for reciprocating the rack bar 65.

The member 103 is also connected through suitable indexing means 113 to the workdriving spindle 114, this spindle being supported at one end in the bushing 115 carried by the sleeve 105, and at the other end in the tapered bearing 116 formed in the forward wall of the headstock. As thus briefly described, it will be seen that the prime mover 13 actuates through a change gear mechanism and a serially arranged reverser two branch transmissions, one of which serves to rotate the work and the other of which serves to reciprocate the tool supporting slide, and since both are actuated from the same source they may be moved in synchronized relation to one another.

If it is therefore assumed that the member 103 is permanently connected to the work spindle 114, the gear 108 permanently connected for rotating gear 110, and the prime mover actuated, that the tool 35 will be moved with respect to the work in such relation that a single internal thread may be formed in the work piece. Having made these assumptions, it is possible to describe the operation of the machine for cutting single threads which will now be done.

The work is held in an air-operated chuck 117 which may be of any suitable commercial form in which the work is held by a plurality of radially moved jaws 118. These jaws may be connected through suitable mechanism to the draw bar 119 shown in Figure 7 in such a manner that movement of the draw bar to the left, for instance, will effect clamping of the work and movement to the right will release the work. The air cylinder such as 120 may be secured to the end of the spindle 114 for rotation therewith and the draw bar connected to a conventional piston mounted in the cylinder. Fluid pressure may be admitted to opposite ends of the cylinder through pipes 121 and 122 and controlled by the manually operable valve 123 having the operating handle 124. A source of fluid pressure may be connected to the supply pipe 125 which terminates in a receiving port in the valve. The lever 124 thus constitutes means for controlling the clamping and unclamping of work in the chuck 117.

After the work has been secured in the chuck the tool spindle is adjusted to the desired angularity by the control lever 43 all in a manner as previously explained. This angularity will of

course depend on the angle of the thread being cut.

The stop screw 61 is now adjusted to limit the manual movement of the slide 52 and position the cutter in a proper starting position with respect to the work. The manual movement of the slide 52 is effected by the hand wheel 72 through the mechanism previously described and shown in Figure 3 of the drawings. When the bar 65 abuts 10 the end 64 of the screw 61, the hand lever 76 is operated to clamp the slide 52 with the rack bar 65. The relationship of axial movement of the tool per revolution of the chuck or, in other words the number of threads per inch is determined 15 by interchangeable pairs of threaded members comprising a screw member 126 and nut member 127 shown more particularly in Figure 7. In other words, a screw and nut of the same number of threads per inch as the thread to be 20 cut are selected and detachably secured in the machine. This is accomplished in the following manner: The bar 65 has a reduced rounded portion 128 and at the intersection of this portion with the main portion a pair of flattened surfaces 129 are formed for interengagement with 25 similar formed surfaces in the end of the bore of the screw member 126. A nut 130 is threaded on the end of the reduced portion 128 for forcing the screw into engagement with these flattened 30 surfaces to insure that the screw member will not be rotated by rotation of the nut. The rod 65 is in turn held against rotation by a key roller 130' engaging a spline 131 formed longitudinally of the bar 65.

35 The nut member 127 is mounted in a counter-bore 132 formed in the end of member 112 and fixed for rotation therewith as by a key 133 and held in position therewith by the threaded locking member 134. It will now be seen that by removing the locking member 134 and the nut 130 that the screw and nut 126 and 127 may be removed from the machine, and other pairs having 40 different pitch threads substituted therefor.

It is necessary in the manufacture of bottle 45 molds to start the thread at a predetermined point in the circumference of the mold, such as at the parting line between the mold sections and if the work is not originally positioned in the chuck to obtain this relative position, the 50 work spindle may be manually rotated to this position by means of a hand wheel 135 which is secured to the end of shaft 95 as more particularly shown in Figure 5 of the drawings.

After the tool has been moved to starting position, and the work properly oriented, the motor 14 is started and the tool sunk to proper depth by rotation of hand wheel 56. The clutch member 96 is then shifted through operation of the hand lever 136 which is secured to the projecting end 60 of shaft 137, as more particularly shown in Figure 8. The inner end of this shaft is supported in a fixed part 138 of the casting which is in turn cut away to provide room for the arm 139 which is pinned to the end of shaft 137 for operating the shifter fork 97 through pin 140. Engagement of 65 this clutch on one side causes rotation of the work and axial movement of the cutter. Trip control means have been provided for stopping the relative movement therebetween, which may vary in 70 increments from a few degrees up to more than two complete revolutions.

After tripping out to stop the advancing movement of the cutter, the reversing clutch is thrown to the opposite side by hand to cause return movement, and the tripping mechanism will again

automatically throw the reversing clutch to neutral position to stop the parts in their original starting position. The slide 52 may now be retracted by hand to permit re-loading the machine.

A novel trip mechanism has been provided for stopping relative advance between the cutter and work after a predetermined angular movement which is effective for less than a full revolution or greater than one revolution. For purposes of explanation there will be considered first the set-up of the mechanism for fractional revolutions of the work head because this is the simplest form. The trip shaft 98 in Figure 8 has a splined projecting end 141 upon which are mounted two trip levers 142 and 143 which, as shown in Figure 6, are so mounted on the shaft that the arms diverge from one another. It will also be noted from Figure 8 that these arms lie in different planes whereby a trip dog that will operate upon one will not in any way interfere with the other. The trip arm 143 is utilized for stopping the return movement and may be designated as the return stop lever and the arm 142 is utilized to stop the cutting or feeding movement and may be designated as the feed stop lever.

Assuming the angle of revolution of the work head to be 320 degrees for instance, which it will be noted is less than a complete revolution, the dog wheel 103 is provided with suitable dogs for tripping the respective levers at the completion of the feeding and return movements. To this end the dog wheel is provided with a pair of T-slots 144 and 145 formed in its periphery, and intermediate these T-slots there is provided a series of graduations as more particularly shown in Figures 14b and 14a respectively. The trip dog 146 which actuates the return stop lever 143 is mounted in the T-slot 145 and secured therein by a conventional T-headed bolt 147 as more particularly shown in Figure 14b. Since the return stop position must be the same as the starting position, and since the starting position must always be the same, the dog wheel 103 may be assumed to have a starting position such as shown in Figure 14 in which the zero graduation 35 thereon is so positioned that the dog 146 may be aligned therewith, and when so aligned will have moved the trip lever 143 to such a position that the reversing clutch is thrown to a neutral or stop position. It is intended that the graduations which, by the way, merely divide the periphery of the dog wheel into degrees shall be utilized for 40 positioning both the trip dogs and due to the divergence of the arms 142 and 143 the dog 146 has a mark or line 148 inscribed thereon which 45 may be utilized for positioning the dog and in this case placed in radial alignment with the zero graduation.

The other dog 149 is mounted in the T-slot 144 and is of similar shape to dog 146 with the exception that the actuating portion 149' thereof is centrally located with respect to the base of the dog rather than off-set as in dog 146. This relationship is particularly shown in Figures 14a and 14b respectively. This dog also has a locating mark 150 suitably placed thereon for positioning the same with the aid of the graduations on the dog wheel. The marks 148 and 150 are on adjacent sides of the dogs so that if both of these marks were aligned with the zero mark the head would be rotated a complete revolution and stopped. Due to the fact, however, that the dog wheel must move through an angle of substantially 8 degrees in order to effect tripping after contacting the trip lever, it is not possible to ob-

tain a full revolution with this simple set-up. The dog 149 is aligned with the 320 degree graduation as shown in Figure 14a and the dog 146 aligned with the zero graduation. Attention is invited to the fact that in this set-up the trip lever 142 is secured to the trip shaft 98 in spaced relation with respect to lever 143, Figure 14b, and in alignment with a mark 151 appearing near the outer end of the shaft. This will position the arm 142 in the plane of the operating portion of dog 149.

When the clutch 96 is thrown to a feeding position, the dog wheel 103 will rotate in the direction of arrow 152, Figure 14, and will continue to rotate until the trip lever 142 is operated which will thereby rotate shaft 98, and through the splined portion 93 on the shaft will actuate the shifter fork 97 and move the clutch to a stop position. In other words, the lever 142 will be in the position 142' before it is tripped by the dog and will be moved to the full line position shown, after tripping by the dog.

The return movement is initiated by the operator throwing the lever 136 to continue the movement of the clutch to its opposite position which will thereby move the trip levers to the dash and dot line position shown in Figure 14. This will move lever 142 completely out of the path of dog 149 and position the trip arm 143 in the path of dog 146 so that upon counter-clockwise rotation of the dog wheel 103 it may be engaged and the clutch returned to a stop position.

From the foregoing, it will be seen that in order to set up the machine for cutting single threads of less than a full revolution, that the operator merely positions the dog 149 to the angular position desired by aid of the graduations on the dog wheel and move the trip lever 142 into alignment with the mark 151. As previously stated, since the stop position is always the same, it is never necessary to re-adjust the trip lever 143 or the stop dog 146.

As an aid to the operator, the dog wheel has another series of graduations thereon, as more particularly shown in Figure 14a which are the same as the previous set of graduations with the exception that the zero mark is at the front of the machine to align with a fixed pointer whereby the operator may observe during operation of the machine the amount of angular movement through which the head rotates because the zero mark of the first set of graduations is really positioned for observation from the back of the machine and therefore of no aid to the operator when he is in the normal machine operating position.

The relative position of the tripping parts for stopping rotation of the work head after angular movement through one revolution or plus fractions of another is shown in Figure 16. As previously mentioned, it is necessary first that the dog 149 pass the trip lever 142 without actuating the same during the first time around, and to actuate the same the second time around. Additionally, the parts must be so positioned that during the return movement the return stop dog will pass trip lever 143 the first time and actuate it the second time. These effects are produced by shifting the trip lever 142 to a second position which is that shown in full lines in Figure 16. The operator is guided in this positioning movement by a second locating mark 153 appearing on the shaft 98. The dog 149 is properly positioned at the desired angle and the feed rotation started. After the dog 149 passes arm

142 the first time, the shaft 98 is indexed axially toward the left to its dot and dash line position Figure 16, to move the trip levers 142 and 143 to the left. This indexing movement is effected by the following mechanism:

Referring to Figure 8, the shaft 98 has circular rack teeth 154 cut on its periphery for engagement with the gear segment 155. The gear segment is pivotally mounted on a shaft 156 and has an integral ball-ended lever 157 engaging a slot 158 formed in the periphery of an axially movable sleeve 159. The sleeve is supported by a shaft 160 and is moved axially relative to the shaft by means of a pin 161 which is fixed for rotation with the shaft and has a projecting end 10 engaging an internal spiral groove 162 formed in the sleeve.

The shaft 160 has a star wheel 163 secured to the projecting end thereof, the fingers 163a and 163b on the wheel lying in the plane of an operating dog 164 as more particularly shown in Figure 15. The dog is secured by a conventional T-bolt in the T-slot 144. As the dog 164 passes the star wheel, the latter is rotated through an angle of substantially 90 degrees which thereby 20 through the pin 161 and spiral groove 162 axially moves the sleeve 159 toward the right a sufficient amount to index the shaft 98 and place the trip arm 142 in the plane of its operating dog 149. This not only positions the parts for 25 tripping the clutch 96 to a stop position to terminate the feed movement, but also moves the lever 143 out of the plane of its operating dog 146 so that when the clutch 96 is engaged for return movement the dog 146 may pass the trip 30 lever 143 the first time and reversely operate the star wheel the next time.

Attention is invited to the fact that the dog 164 actually rotates the star wheel through a greater angle than 90 degrees in order to get past the 40 same, but a spring pressed detent 165, Figure 6, aids in returning the star wheel through a small angle after the dog passes. This makes it possible for the star wheel to be in a position to be engaged by the dog 164 on its return movement. 45

The set-up for rotation of the work head through two revolutions or more is shown in Figure 17, and the only necessary change is to move the trip lever 142 inwardly to a third position in which it abuts the end of lever 143, and then 50 suitably position the dog 149 to the proper angle. In this case, the operation is the same with the exception that the dog 164 indexes the star wheel twice which becomes necessary in order to move the trip lever 142 outwardly into the proper plane 55 with its operating dog. This permits the dog 149 to pass the trip lever twice without actuating the same, but will effect actuation thereof the third time. It also moves the trip lever 143 a sufficient distance that upon the return movement 60 star wheel must be indexed twice in an opposite direction in order to get the lever 143 back into the plane of its operating dog.

The trip control mechanism just described may be utilized not only for cutting single threads but also utilized for cutting multiple threads. The previous description of machine operation was based upon the assumption that the dog wheel 103 was permanently connected to the sleeve 105 and that the gear 108 was permanently connected with the gear 110 for the purpose of showing how the machine may be operated in a simple manner for cutting single threads. When the machine is operated for cutting multiple threads, certain changes in the set-up of the machine have to be 75

made and the first is to make provision for suitably indexing the work dependent upon the number of multiple threads being cut. The indexing is provided for by utilizing a sliding clutch member 5 166 which, as shown in Figure 7, is connected by the key 167 to the sleeve 168, this sleeve being keyed to and surrounding the work spindle 114. The sleeve has a tapered bore 169 which fits on the tapered end of the spindle 114 and held in 10 place by the lock nut 170. The sliding clutch 166 is moved back and forth by the manually operable lever 171 which, as shown in Figure 1, is pivotally mounted at 172 on a fixed part of the headstock. A spring actuated plunger 173 serves to 15 normally maintain the clutch in an engaged position.

The dog wheel 103 is provided with a clutch ring 174 fixedly secured to the end of the dog wheel and has clutch teeth of a complementary 20 shape to inter-engage the clutch teeth of member 166. From this it will be seen that when the lever 171 is moved to the left as viewed in Figure 1, the work spindle 114 is disconnected from the dog wheel 103 which serves as a driving member therefor, and during this disconnection, the work fixture 117 may be rotated by means of the hand wheel 175 secured thereto so as to position the work without disturbing the other mechanism.

It will be obvious that the indexing angle will 30 vary in accordance with the number of multiple threads, that is if a double thread is being cut the work should be indexed 180 degrees, or if a triple thread is being cut the work should be indexed 120 degrees, and so on. Ordinarily, this 35 would require great care on the part of the operator with present devices in performing this indexing and the liability of error is very great. In the present machine, however, an index angle selector has been provided which may be pre-set 40 in accordance with the number of multiple threads being cut whereby the indexing becomes a very simple operation, it merely requiring the operator to move the lever 171 to the left a sufficient amount to permit independent rotation of 45 the work fixture, then to release the lever 171 and continue the rotary movement by hand wheel 175 until the clutch snaps into position again. When the clutch snaps into position by the spring pressed plungers 173 this will be the 50 signal that the proper amount of indexing has been effected. The means which simplifies this operation comprises a guard ring 176 which is mounted on and surrounds the clutch ring 174. This guard ring as shown in Figures 18 to 21 55 inclusive has a plurality of irregular spaced teeth and slots cut therein which are adapted to cooperate with one radially elongated tooth 177 of the sliding clutch member 166. In other words, the guard ring has the tooth spacings so arranged that as shown in Figure 18 the elongated tooth 177 is prevented from returning to an engaged position except at two points which are at opposite ends of diameter 177a and therefore 180 degrees apart. This insures that the operator 60 can only index the work by 180 degree increments if the above procedure is followed.

In Figure 19 the guard ring is shown in a circumferentially adjusted position with respect to its supporting clutch member 174 so as to permit the engagement of tooth 177 in six different circumferential positions at the ends of diameters 177a, 177b, and 177c, and thereby permit the cutting of six multiple threads. In Figure 20 the guard ring is shown in a second adjusted position to permit four indexings per revolution and

the cutting of four multiple threads and in Figure 21 the guard ring is shown in another position to permit the cutting of triple threads. The guard ring is detachably secured to the clutch ring 174 by a filister-headed screw 178 Figure 22, and the head of this screw is inserted in the counter-bore 179 for securing the guard ring in the position shown in Figure 18; in counterbore 180 for securing the guard ring in a position shown in Figure 19; in counterbore 181 for securing the guard ring in a position shown in Figure 20; and the counterbore 182 for securing the guard ring in the position shown in Figure 21. Suitable markings such as 183 may be made on the guard ring and in suitable position about the periphery thereof whereby they are readily observable from the operator's position at the front of the machine.

When cutting single threads, the gear 108 is positively connected to the gear 110 and through the following means. The gear 110 is secured as by the key 184 to the shaft 109, and this shaft also has splined thereon the slidable member 185. This member has an annular groove 186 formed in the periphery thereof in which is fitted a shoe 187 carried at the end of lever 188, Figure 5, the lever being secured to the shaft 189 which extends through the headstock casing and provided with a manually operable lever 190. This lever has a knurled hand grip 191 which is spring mounted in the end thereof to maintain the same in various adjusted positions by engagement with a series of notches 92 formed in the casting, as more particularly shown in Figure 1. When the member 185 is in the central position shown in Figure 7, the spring pressed plungers 193 move radially outward, as shown in Figure 12, to connect the shaft 109 with the clutch ring 194 secured as by bolts 195 to the periphery of the gear 108. It will be noted from Figure 12 that the ends of plungers 193 are tapered on one side for engaging the tapered side 196 of slots 197 formed in ring 194. The gear 108 rotates in the direction of arrow 198 during the feeding movement and to all intents and purposes this forms a positive driving connection because the spring 199 is sufficiently strong to prevent radially inward movement of plungers 193 when only imposed with the duty of moving the work support. This constitutes the connection when ordinary spiral threads are being cut.

By a simple adjustment of member 185, the machine may be transformed for cutting closed annular grooves, and in this case it is merely necessary to shift the member 185 to the left as viewed in Figure 7. This causes the inner cone surface 200 on the end of member 185 to engage the beveled end 201 of plungers 193 and move the same inward to disengage their ends from the slots 197. This will permit rotation of gear 108 without rotating shaft 109.

It is also possible to cut with this machine a groove having a configuration such as that shown in Figure 23 which has a partly spiral portion, such as 202, similar to a spiral thread, and a straight portion or annular portion 203. This irregular shaped groove may be cut in a single continuous operation by this machine and is accomplished by shifting the member 185 to the right as viewed in Figure 7.

In forming this groove the spiral portion is cut first and since the plungers 193 can move radially outward, the gear 108 is permitted to drive gear 110. When the machine is in the starting position a pair of longitudinally extending splines or

grooves 204 formed on the periphery of member 185 are in alignment with a pair of spring pressed plungers 205 more particularly shown in Figure 11, and these plungers have bevel shaped ends 206 which engage the beveled side 207 of the splines 204. The plungers 205 are carried in a circumferentially adjustable member 208 which has a knurled portion 209 projecting beyond the headstock casting and a plurality of clamping bolts 210. The beveled face 211 of the member 208 is graduated as shown in Figure 10 and a double ended pointer 212 is fixed to the end of shaft 109 which projects through the member 208. When the parts are in a starting position, the 15 pointer registers with the zero marks. If now, it is desired that the spiral groove shall have a predetermined angular extent of any amount up to 180 degrees, the clamping bolts 210 are loosened and the member 208 rotated until the proper 20 graduation is opposite the pointer and then the clamping bolts are re-tightened. The member 208 is rotated in the direction of arrow 213, Figure 11, which thereby causes retraction of the plungers 205 due to their beveled ends which are 25 in such a direction that this retraction can automatically take place. After this adjustment has been made, the machine is started and the shaft 109 will rotate in the direction of arrow 214 thereby carrying the sleeve 185 with it, which 30 movement will continue until the splines in the member 185 come opposite to the plungers 205, at which time the plungers will snap home into the grooves and prevent further rotation of member 185 and thereby of shaft 109 which will cause 35 slippage of the clutch ring 194 due to depression of plungers 193, Figure 12, and the inward feed of the cutter spindle will be prevented but the work will continue to rotate and thereby form the straight portion 203 of the configuration 40 shown in Figure 23.

Upon reversal of clutch 96 the gear 108 will be rotated in a counter-clockwise direction, or in other words opposite to the direction of arrow 198, and since the plungers 193 are at this time 45 depressed and riding against the inner bore of clutch ring 194 the tool will not be moved until this rotation has continued a sufficient amount to permit the plungers 193 to snap radially outward into the slots 197. When this occurs the 50 shaft 109 will be positively driven, and this will cause depression of plungers 205 and thereby rotation of shaft 109 which will then cause return movement of the cutter along a spiral path to its starting position.

55 What is claimed is:

1. In an internal milling machine the combination of a work support, a slide movable toward and from the work support, a carrier adjustably mounted in arcuate guideways on the slide, a tool spindle, an adjustable quill for supporting the tool spindle in the carrier, and means to adjust said quill in a direction to position the center of the tool coincident with the center of curvature of said arcuate guideways.
- 65 2. In a thread milling machine having a rotatable work support and a rotatable tool spindle having a cutter mounted on the end thereof, the combination of means for supporting the tool spindle for angular adjustment with respect to the axis of the work support including an upright having arcuate guideways therein, a carrier adjustably mounted in said guideways, a quill supporting the tool spindle in said carrier for longitudinal adjustment whereby the center 70 of rotation of the cutter may be positioned co-

incident with the center of curvature of said guideways, and means for adjusting said carrier including a cooperating screw and nut, one of which is attached to the carrier, and the other pivotally supported in said upright.

3. In a thread milling machine having a rotatable work support and a rotatable tool spindle having a cutter mounted on the end thereof, the combination of means for supporting the tool spindle for angular adjustment with respect to the axis of the work support including an upright having arcuate guideways therein, a carrier adjustably mounted in said guideways, a quill supporting the tool spindle in said carrier for longitudinal adjustment whereby the center of rotation of the cutter may be positioned coincident with the center of curvature of said guideways, means for adjusting said carrier including a cooperating screw and nut one of which is attached to the carrier, and the other to the upright, manual means for moving the upright and thereby the spindle to determine the eccentric adjustment of the center of rotation of the tool spindle with respect to the center of the work support, and an adjustable stop for limiting said movement.

4. In a thread cutting machine the combination of a headstock, a work supporting spindle journaled in said headstock, a tailstock, a tool spindle having a cutter secured to the end thereof of journaled in said tailstock, means to revolve the axis of the tool spindle above and below the plane of said work spindle in accordance with the pitch of the thread being cut, means for feeding the tailstock toward and from the headstock including a prime mover, motion transmitting means extending therefrom for rotation of the work spindle, a longitudinally reciprocable member extending between said stocks, means to connect said member for reciprocation by said prime mover, and means to disconnect the tailstock from said member for manual adjustment to a work loading position.

5. In a threading machine having a work support and a tool support, and a work spindle and a tool spindle journaled in the respective supports, the combination of means for effecting relative movement between said supports to cut a thread in the work including a prime mover carried by one of said supports, branch transmissions for rotating the work spindle, and for effecting relative movement between the supports, a reverser mechanism connecting the branch transmissions with said prime mover, and power trip means actuatable by one of said branch transmissions for shifting said reverser to a stop position.

6. In a threading machine having a work support and a tool support, and a work spindle and a tool spindle journaled in the respective supports, the combination of means for effecting relative movement between said supports to cut a thread in the work including a prime mover carried by one of said supports, branch transmissions for rotating the work spindle, and for effecting relative movement between the supports, a reverser mechanism connecting the branch transmissions with said prime mover, power trip means actuatable by one of said branch transmissions for shifting said reverser to a stop position, and inter-changeable means in the other branch transmission for varying the rate of movement of the tool support with respect to a single rotation of the work spindle to thereby change the lead of the screw being cut.

7. In a threading machine having a work support and a tool support, and a work spindle and a tool spindle journaled in the respective supports, the combination of means for effecting relative movement between said supports to cut a thread in the work including a prime mover carried by one of said supports, branch transmissions for rotating the work spindle and for effecting relative movement between the supports, a reverser mechanism connecting the branch transmissions with said prime mover, power trip means actuatable by one of said branch transmissions for shifting said reverser to a stop position, inter-changeable means in the other branch transmission for varying the rate of movement of the tool support with respect to a single rotation of the work spindle to thereby change the lead of the screw being cut, one of said transmissions also having means for indexing the work spindle relative to the power driving means whereby multiple threads may be cut in the work.
8. In a threading machine the combination of a work support, a thread cutting tool, a power driven member operatively connected for effecting a relative rotation and a relative feeding movement simultaneously between the work support and tool, and means including a multiple thread index angle selector between said member and the work support, and means to index the work through angles determined by said selector.
9. In a thread cutting machine having a rotatable work support and a thread cutting tool, the combination of means for effecting a relative spiral feeding movement between the support and tool including a power operable member for rotating the work support, a member shiftable between two positions for effecting connection and disconnection of the power driven member with respect to the work support, means normally maintaining said connection, manually operable means for effecting said disconnection, and additional manually operable means for rotating the work support during said disconnection to index the work with respect to the driving means for the purpose of cutting multiple threads.
10. In a multiple thread cutting machine having a rotatable work receiving spindle and a threading tool, a power transmission for effecting relative movement between the spindle and tool, said transmission including a power rotatable member, a shiftable member operatively connected with the work spindle, complementary inter-engaging teeth forming a driving connection between said members, manually operable means for retracting said shiftable member, manually operable means for rotating the work when disconnected from said power member, resilient means normally urging said members into mutual engagement, and means adapted to be pre-set to prevent said mutual engagement until the work has been manually rotated through a predetermined angle dependent upon the number of multiple threads to be cut on the work.
11. In a threading machine having a rotatable work receiving spindle, the combination of means for indexing said spindle relative to a thread cutting tool whereby multiple threads may be cut including a first multiple toothed reference member, a second multiple toothed member permanently connected for rotation with the work spindle and slidable relative thereto to effect engagement and dis-engagement of the teeth of said members, and means intervening between
- said members including a tooth and a multiple slotted guard ring attached to the respective members, said multiple slotted ring cooperating with the teeth on one of said members to prevent mutual re-engagement of the teeth until the work has been rotated through a predetermined angle.
12. In a machine tool having a rotatable work support and a tool support, the combination of a power operable transmission including a first branch for rotating the work, a second branch, a shiftable member having a first position for connecting said second branch to cause a relative spiral feeding movement between the tool and work for thread cutting purposes, and a second position for disconnecting said second branch whereby the machine is conditioned for cutting annular grooves, means to move said member to a third position, a prepositionable stop for engaging said member to interrupt said spiral feed movement to limit the length of a spiral cut, and ratchet means adapted to yield upon continued rotation of said second branch to effect continued rotation of the work without feeding movement of the tool whereby an annular groove may be formed in continuity with said spiral groove.
13. In a threading machine having a work support and a tool support, the combination of power operable means for generating a spiral cutting path between the supports to form a thread, a clutch in said transmission having a motion interrupting position and power transmitting positions on either side thereof, manually operable means for shifting said clutch to one of its power transmitting positions, and means for shifting said clutch to a motion interrupting position after a predetermined relative angular movement between the work support and tool support including a rotatable dog wheel driven by said transmission through said clutch, a trip plunger mounted adjacent the periphery of said wheel, motion transmitting means connecting said plunger with the clutch, and graduations on said dog wheel for prepositioning the trip dog a predetermined angular distance from said trip plunger whereby after rotation of the dog wheel through said predetermined angle the relative spiral movement between the work and tool will be terminated.
14. In a threading machine having relatively, movable work and tool supports, for generating a spiral cutting path, the combination with transmission means for effecting said movement, of trip operable means for determining the length of said path after one or more revolutions including a trip plunger, a motion interrupting clutch in said transmission operatively connected with said trip plunger, a trip dog movable in accordance with the rotary component of said spiral movement, a trip lever adjustably positioned on said trip plunger whereby it may be placed in the path of said dog for engagement therewith during the first revolution thereof; or out of the path of said dog, and means subsequently operable after the dog has passed the trip plunger one or more times for axially indexing said plunger to position the trip lever in the path of said dog whereby said clutch will not be shifted until after one or more complete revolutions of the trip dog.
15. In a threading machine having relatively movable work and tool supports for generating a spiral cutting path, the combination with transmission means for effecting said movement, of trip operable means for determining the length

of said path after one or more revolutions including a trip plunger, a motion interrupting clutch in said transmission operatively connected with said trip plunger, a trip dog movable in accordance with the rotary component of said spiral movement, a trip lever adjustably positioned on said trip plunger whereby it may be placed in the path of said dog for engagement therewith during the first revolution thereof; or out of the path of said dog, means subsequently operable after the dog has passed the trip plunger one or more times for axially indexing said plunger to position the trip lever in the path of said dog whereby said clutch will not be shifted until after one or more complete revolutions of the trip dog, said last named means including a star wheel and a second trip dog movable in unison

with the first dog, and means operable by the star wheel for indexing said trip shaft.

16. In a threading machine having a work support, the combination of a tool support movable toward and from the work support including a 5 tool spindle, a carrier for supporting the spindle, an upright, means for adjustably mounting the carrier on one side of said upright, a prime mover mounted on said carrier at the opposite side of said upright and with its axis extending in a 10 direction parallel to the axis of said spindle, a power transmitting band for transmitting motion to the spindle from said motor, and means to pivotally support said motor on said carrier for adjustment in a direction to vary the tension 15 in said transmitting band.

WALTER D. ARCHEA.

CERTIFICATE OF CORRECTION.

August 24, 1937.

Patent No. 2,090,992.

WALTER D. ARCHEA.

It is hereby certified that error appears in the printed specification of the above numbered patent requiring correction as follows: Page 8, first column, line 58, claim 10, after the word "work" insert spindle; and that the said Letters Patent should be read with this correction therein that the same may conform to the record of the case in the Patent Office.

Signed and sealed this 21st day of September, A. D. 1937.

Signed and sealed this 21st day of September, A. D. 1937.
